UNITED STATES PATENT OFFICE.

ELVAH O. BULMAN, OF GRAND RAPIDS, MICHIGAN.

PAPER-ROLL HOLDER AND CUTTER.

1,400,521.

Specification of Letters Patent. Patented Dec. 20, 1921.

Application filed March 28, 1921. Serial No. 456,100.

To all whom it may concern:

Be it known that I, ELVAH O. BULMAN, a citizen of the United States, residing at Grand Rapids, in the county of Kent and 5 State of Michigan, have invented new and useful Improvements in Paper-Roll Holders and Cutters, of which the following is a specification.

The present invention relates to paper-10 roll holders and cutters; and its object is, generally, to provide a device of that character which may be very economically constructed and may be readily and efficiently operated; and, more particularly, to provide 15 such a device having improved arms for the cutters thereof and improved mountings therefor; and further, to provide improved means for releasably holding the cutter of such a device in contact with the paper roll; 20 and further, to provide improved means for joining the arms and cutting bar of the cutter together.

These objects are attained by, and the invention finds preferable embodiment in, the 25 structure hereinafter particularly described and illustrated by the accompanying drawings, in which:—

Figure 1 is a front view of a paper-roll holder and cutter, one of the supports being 30 shown in central vertical section and certain parts being broken away;

Fig. 2 is a side view of one of the supports and associated parts, certain parts being broken away and certain parts being 35 shown in vertical section;

Fig. 3 is a like view showing the parts in another position;

Fig. 4 is a view of certain parts, some of 40 which are sectioned on line 4—4 of Fig. 2; and

Fig. 5 is a view of certain parts partially sectioned on line 5—5 of Fig. 1.

In the embodiment of the invention chosen for illustration by the drawings and for detailed description in the body of this specification, my paper-roll holder and cutter has a pair of upright supports 1 suitably secured at their lower ends to a base indicated at 2 and connected at their upper ends by a 45 cross bar 3. These supports carry pivot pins 4, such pins being desirably secured to the body members of their supports by being passed through openings 5 therein and also to the members 6 of the supports by being 50 passed through openings 7 therein, said members 6 being spaced apart from the

bodies of the supports and secured thereto in suitable manner as by the ends 8 of the members 6 being passed through openings 9 in the body members of the supports and 60 thereupon upset to join said members together.

The cutter, designated generally 10, comprises a cutting bar 11 whose outer or cutting edge contacts with the paper-roll (not 65 shown) turnably supported on the rod 12 whose ends are removably held by the struck-up tongues 13, 14 of the supports, and said cutter also comprises the supporting arms 15 whose inner ends are bent over to form 70 integral spaced-apart portions 15, 16 parallelly disposed, and the bight portion 17 between them, said portions 15, 16 lying between the body of the support and its member 6. The pivot pins 4 pass through alined 75 orifices 18 in the arms' portions 15, 16, the arms thus bearing rockably on the pivot pins. The bight portion 17 has an aperture 19 forming a rock member 20 at one side thereof whose axis is spaced from the axis 80 of the pivot pin. A plunger 21 slidable and swingable in a bearing 22 on the support has spaced-apart lugs 23 between whch the rock member 20 bears. A spring 24 presses the plunger into such bearing engagement with 85 the rock member and urges the cutting bar into contact with the paper-roll in the operative position of said bar shown in Fig. 2: When however the cutter is swung upwardly 90 on the pivot pins and into the position seen in Fig. 3, the rock member 20 passes to the opposite side of the pivot pin's axis whereby the cutter is held upwardly and free from the paper-roll.

The corresponding edges 25 of the arms 95 15 have recesses 26 and their free ends have reduced portions 27 received in the apertures 28 of the cutting bar and held therein as by turning over such reduced ends. In this assembled position of the parts of the 100 cutter, the outer edge 29 of the longitudinally extending flange 30 of the cutting bar is seated in the recesses 26 whereby a rigid connection of the cutting bar 11 and supporting arms 15 is provided.

The cutter may be pivotally mounted as above described on only one of the supports, such support alone carrying the plunger and associated parts, the cutter in such case being pivotally mounted on the other support 110 in any suitable manner.

The invention being intended to be point-

ed out in the claims, is not to be limited to or by details of construction of the particular embodiment thereof illustrated by the drawings or hereinbefore described.

5 I claim:

1. In a device of the character described; a support carrying a pivot pin; a cutter comprising a cutting bar and a supporting arm therefor having integral spaced-apart portions parallelly disposed and provided with aligned orifices therethrough rockably bearing on the pivot pin and having also an integral bight portion between said parallelly disposed portions provided with an aperture and a rock member at one side thereof; a spring-pressed plunger slidable
- 10
- 15

and swingable in a bearing on the support and having spaced-apart lugs between which said rock-member bears.

2. In a device of the character described; 20 a support; a cutter having an arm rockably mounted on the support and provided with a member spaced from the axis of the arm's mounting; a spring-pressed plunger 25 slidable and swingable in a bearing on the support to positions on the opposite sides of said axis and having a bearing on the rock member.

In testimony whereof I have hereunto set my hand at Grand Rapids, Michigan, this 22nd day of March, 1921.

ELVAH O. BULMAN.
